(57) **CLAIM**

The ornamental design for a silicon wafer for solar battery, as shown and described.

DESCRIPTION

FIG. 1 is a perspective view of a silicon wafer for solar battery showing my new design;

FIG. 2 is a front elevational view thereof, the rear elevational view being a mirror image;

FIG. 3 is a side elevational view thereof, the opposite side being a mirror image; and,

FIG. 4 is a top plan view thereof.
